UNITED STATES PATENT OFFICE.

HARRY J. SMITH, OF BEND, OREGON.

WRENCH.

1,388,005.

Specification of Letters Patent. Patented Aug. 16, 1921.

Application filed September 3, 1920. Serial No. 407,866.

To all whom it may concern:

Be it known that I, HARRY J. SMITH, a citizen of the United States, residing at Bend, in the county of Deschutes and State 5 of Oregon, have invented certain new and useful Improvements in Wrenches; and I do hereby declare the following to be a full, clear, and exact description of the invention, such as will enable others skilled in the art 10 to which it appertains to make and use the same.

This invention has relation to certain new and useful improvements in a wrench and has for its primary object the provision of a 15 simple form of sliding jaw wrench which will be strong and durable as well as highly efficient in use and comparatively inexpensive and which may be readily assembled or adjusted.

20 This invention has for another object the provision of a wrench of the character stated in which the shank of the sliding jaw may be readily released and adjusted and then securely locked in position at the minimum 25 expenditure of time and effort.

The invention has for a further object the provision of a wrench of the character stated including novel means for operating and guiding the sliding shank and means within 30 the hollow handle for limiting movement of the sliding shank in one direction, the stationary inner jaw limiting movement of the slidable shank and sliding jaw in the reverse direction.

35 With the foregoing and other objects in view as will appear as the description proceeds, the invention consists in the novel construction, combination and arrangement of coöperating elements as hereinafter more 40 specifically set forth, claimed and shown in the accompanying drawings forming a part of the present application and in which:

Figure 1 is an elevation of a wrench constructed in accordance with this invention.

45 Fig. 2 is a longitudinal section therethrough.

Fig. 3 is a transverse section on the plane of line 3—3 of Fig. 1, looking in the direction indicated by the arrows.

50 Fig. 4 is a detail longitudinal section taken on the plane of line 4—4 of Fig. 1, looking in the direction indicated by the arrows.

Fig. 5 is a detail view of the shank locking member, removed.

55 Fig. 6 is a detail of the shank guiding and movement limiting member, removed.

Referring more in detail to the drawings, in which similar reference characters designate corresponding parts throughout the several views, 1 indicates the skeleton body 60 of the wrench upon the outer or forward end of which is formed the stationary jaw 2 while the enlarged hollow handle 3 projects from the opposite end of the body 1 and is connected therewith by the neck portion 4 65 at the inner end of the skeleton body 1 and having opposite open side portions 5, the purpose of which will presently appear. It will also be seen that the outer or rear end of the hollow handle 3 is rounded and the 70 opposite sides are left open, to be closed by side handle plates or members 6 which are adapted to be secured upon opposite sides of the handle 3 by suitable screws 10 passed therethrough and through the opposite upper and lower lugs 11 which are directed toward each other from the upper and lower 75 portions of the handle 3, as clearly shown in Fig. 2 of the drawings. These lugs 11 have flat rear faces 12, the purpose of which will 80 presently appear. These lugs 11 also have flat opposed faces 13 spaced a suitable distance apart to permit passage therebetween of the opposite narrow edges of the shank 8 having the movable jaw or slidable jaw 7 85 formed rigid upon its outer or forward end. The shank 8 is provided with suitable teeth 9 upon its opposite narrow edges which may be termed its upper and lower edges and the shank 8 is further provided at its rear end 90 with a reduced threaded extension 14, upon which may be threaded the stop nut 15 of such a size as to project beyond the narrow side faces of the shank 8 and beyond the upper and lower edges or narrow edges 95 thereof so as to engage the flat rear faces 12 of the lugs 11 and thereby limit outward or forward movement of the shank 8.

Before the side handle members 6 are secured in position by the securing screws or 100 securing members 10, the nut 15 should be secured in position upon the shank extension 14.

Previous to extending the shank 8 through the neck portion of the wrench, the shank 105 and outer jaw locking ring 16 should be placed within the neck portion 4 and turned so as to permit the shank 8 to be passed therethrough. The ring 16 is provided at one or more places on its inner face with the locking threads which are adapted to engage 110 even the upper or lower threads of the shank

8 to lock the same against longitudinal movement. The remainder of the inner face of the ring 16 is smooth so as to permit free longitudinal movement of the shank 8 there-
5 through when the threads 17 are disengaged from the threads 9 of the shank 8. This ring 16 is also preferably provided on its outer face with suitable recesses or pockets 18 within one of which is engaged the free end
10 or pointed upturned end 19 of a small spring 20 of the leaf spring variety or of some other suitable form and which is secured to the inner face of the portion 4 either at the lower side thereof as shown in the drawings or at
15 the upper side as may be desired. It will be seen that the diametrically opposite portions of the locking pin project through the open side 4 so that the ring 16 may be readily rotated as the wrench is grasped by the
20 handle 3.

From the foregoing, taken in connection with the accompanying drawings, it will be seen that I have provided a simple and efficient form of wrench which may be readily assembled or disassembled and in which the outer jaw 7 may be readily adjusted with respect to the stationary inner jaw 2 and locked in adjusted position.

While the preferred embodiment of the
30 invention has been shown and described, it will be understood that minor changes in the details of construction and arrangement of parts may be resorted to within the scope of what is claimed without departing from
35 the spirit of the invention.

What is claimed is:—

1. A wrench comprising a body portion, a stationary jaw carried at one end of said body portion, a neck formed at the opposite
40 end of said body portion and having open sides, a handle projecting from said neck and having open sides, side handle members for closing the open sides of the handle, a shank slideable through said body and through the neck and the handle, an outer jaw carried by said shank, means within
45 said neck for locking the shank in adjusted position to prevent movement of the outer jaw with respect to the inner jaw, and means
50 within said handle to limit outward movement of said shank.

2. A wrench comprising a skeleton body having a rigid jaw formed at one end and a neck at the opposite end, a handle extended
55 from said neck and having open sides, side handle members for closing the open sides of said handle, a shank slideable longitudinally through said skeleton body through the neck and through a portion of the handle, means
60 within said neck and projecting through the

sides thereof to lock the shank against movement, an outer jaw carried by said shank, stop lugs formed within said handle and directed toward one another, said shank being extended between said stop lugs, and
65 means carried by said shank for engagement with said stop lugs to limit outward movement of said shank.

3. A wrench comprising a body, a stationary jaw formed at one end of said body, a neck formed at the opposite end of said body and having open side portions, a handle extended from said neck, a shank slideable through said handle and said body and through said neck, an outer jaw carried by
70 said shank, said shank having threads formed on its upper and lower faces, a ring within said neck and extending through the open side portions thereof, said ring surrounding said shank and having threads on a portion of its inner face for engagement with the threads of said shank to lock the latter against movement, means for resiliently retaining said ring against rotation, said shank having a reduced end extension, a nut
75 threaded on said extension, and means within said handle for co-operation with said nut to limit outward movement of the said shank.

4. A wrench comprising a body portion, a stationary jaw carried by said body portion, a neck formed at one end of said body portion and having open sides, a handle frame extended from said neck, side handle members secured upon said handle frame, a shank slideable through said body and through the neck and the handle, an outer jaw carried by said shank, means for locking the shank in adjusted position with respect to said stationary jaw, and means within said handle to limit outward movement of said shank.

5. A wrench comprising a body having a rigid jaw at one end and a neck at the opposite end, a non-rotatable handle extended from said neck, a shank slideable longitudinally through said body and through the neck and handle, means rotatable within said neck for locking said shank in adjusted position to prevent movement of said shank, an outer jaw carried by said shank for co-operation with said rigid jaw, and means within said handle to limit outward movement of said shank.

In testimony whereof I affix my signature in presence of two witnesses.

HARRY J. SMITH.
